UNITED STATES PATENT OFFICE

129,236

DESIGN FOR A PACKAGED SKIRT

Carmen Larison, Phoenix, Ariz.

Application January 30, 1941, Serial No. 98,552

Term of patent 7 years

To all whom it may concern:

Be it known that I, Carmen Larison, a citizen of the United States, residing at Phoenix, in the county of Maricopa and State of Arizona, have invented a new, original, and ornamental Design for a Packaged Skirt, of which the following is a specification, reference being had to the accompanying drawing, forming part thereof.

The figure is a perspective view of a packaged skirt showing my new design.

The characterizing features of my design reside in a packaged skirt, comprising a crinkled skirt wrapped around a looped carrier stick, with the stick ends protruding beyond the skirt, and spaced tie members wrapped around the skirt, all as shown.

I claim:

The ornamental design for a packaged skirt, as shown and described.

CARMEN LARISON.
